UNITED STATES PATENT OFFICE.

ALBERT L. VENCILL, OF WILKINSBURG, PENNSYLVANIA, ASSIGNOR TO THE UNION SWITCH & SIGNAL COMPANY, OF SWISSVALE, PENNSYLVANIA, A CORPORATION OF PENNSYLVANIA.

RAILWAY SIGNALING SYSTEM.

1,076,176.

Specification of Letters Patent.

Patented Oct. 21, 1913.

Application filed January 29, 1912. Serial No. 674,026.

To all whom it may concern:

Be it known that I, ALBERT L. VENCILL, a citizen of the United States, residing at Wilkinsburg, in the county of Allegheny and State of Pennsylvania, have invented certain new and useful Improvements in Railway Signaling Systems, of which the following is a specification.

My invention relates particularly to automatic signaling systems, that is systems in which the railway signals are controlled automatically by the passage of a car or train, for portions of single track over which traffic moves in both directions; such for example as for stretches of track between passing sidings, and irrespective of the location of the said stretches of track.

I will describe a form of automatic signaling system embodying my invention, and then point out the novel features thereof in claims.

In the accompanying drawings, Figure 1 is a diagrammatic view showing one form of automatic signaling system embodying my invention, showing the usual condition of circuits and apparatus with no car or train present. Figs. 2 and 3 are views similar to Fig. 1 but showing the condition of circuits and apparatus of the system during the passage of a car or train.

Similar reference characters refer to similar parts throughout the several views.

My invention relates to that class of automatic signaling systems in which a stretch of track is protected at both ends by a signal or signals which govern traffic from opposite directions through the stretch; the signal control being so arranged that as a car or train enters the stretch of track the signal at the entering end is caused to indicate "caution," that is, it is caused to give an indication for succeeding cars or trains to follow through the stretch; and the signal at the other end is caused to indicate "danger" or "stop"; and the control being so arranged that as the car or train proceeds through the stretch of track the said indications of the signals are maintained. With the signals giving the indications stated, a succeeding car or train or any number of succeeding cars or trains may follow through the stretch of track under the protection of the "caution" indication, which indication remains until all cars or trains

have passed out of the stretch of track. Of course all train movements in the opposing direction are prevented by reason of the "stop" or "danger" signal at the other end of the stretch of track. I prefer that the railway signals at the two ends of the stretch of track should usually give what is known as their "clear" or "proceed" indication, but I do not wish to be limited to this arrangement.

In the practice of my invention I provide at least two track relays for the stretch of track, one of which relays is opened when a train enters the stretch of track to cause the signal at such entering end to indicate caution, and to cause the signal at the other end of the stretch of track to indicate danger or stop, while the other of the track relays as the train proceeds further is opened to maintain the same condition of the signals. These two track relays may be energized from a single track circuit, in which case the source of signaling current will be located between them, or they may be energized from two or more track circuits. I also provide two signal relays, one for the control of the signal at one end of the stretch of track and the other for the control of the signal at the other end of the stretch of track, which signal relays are controlled by the track relays.

One feature of the form of my invention herein described is the control of the circuits for the signal relays by the contacts of these relays themselves in such manner that when either of these relays is energized its contacts operate to disconnect the other signal relay from its usual circuit and to connect that circuit with the signal relay which is energized, so that when the usual circuit for the second signal relay is then closed and that for the first opened, the first signal relay remains energized and the second remains unaffected.

Another feature of the form of my invention herein described is that it requires only standard apparatus, that is, relays and signals of usual commercial types.

Referring now to the drawings, A designates a stretch of track, here shown as being a section of single track between two passing sidings B and C. Traffic through the stretch A in opposite directions is governed by signals S and S'. As here shown

2

these signals are of the semaphore type, but it is understood that signals of any type—light, semaphore, etc., adapted to give the desired indications may be employed. As 5 here shown the signals are each adapted to give three indications,—danger, caution and clear, although I do not wish to be limited to this specific number of indications. The stretch of track A as here shown is provided with two track circuits *a* and *b* each of which includes a source of signaling current 50 or 51 and a track relay *T* or *T'*. The two track circuits are separated in any suitable manner—as here shown by means 10 of insulation 52 in the rails.

15 *R* and *R'* are two signal relays for the control of the signals. These signal relays may control through suitable circuits all of the indications of these signals, or they may 20 control only one or more of the indications; as here shown, relay *R* controls the caution indication of signal *S*, and relay *R'* controls the caution indication of signal *S'*. The clear indications of the signals are as here 25 shown controlled directly by the track relays *T* and *T'*. The signal relays *R* and *R'* are controlled by the track relays *T* and *T'* as I will now explain.

For each relay *R* and *R'* I provide a circuit, each of which includes a back contact 30 of the other relay. For example, the circuit of relay *R* is from source of current 10 through back contact 11 of track relay *T*, wire 12, back contact 13 of relay *R'*, wire 35 14, relay *R*, wire 15, to source of current 10. The circuits of these relays are so controlled by the track relays *T* and *T'* that as a car or train enters the stretch of track from either end, the circuit of one of the 40 relays *R* or *R'* is closed; when the car or train passes insulation point 52 the circuit for the other relay is closed, and after this second circuit is closed the first one is again opened as the car or train passes entirely off 45 of the first track circuit. The contacts of signal relay *R'* control connections which are so arranged that when this relay is energized it cuts signal relay *R* out of its circuit and connects that circuit with signal 50 relay *R'*; thus when relay *R'* is energized, the normal circuit for relay *R* traced hereinbefore becomes as follows:—from source of current 10 through contact 11, wire 12, contact 13, wires 17 and 18, relay *R'*, wire 55 19 to source 10. The contacts of relay *R* control the circuit for relay *R'* in a similar manner.

Since I have herein shown three-position signals, each signal is provided with a clear 60 indication circuit and a caution indication circuit. In the arrangement of control circuit shown in the drawings, the clear indication circuit for each signal is controlled by front contacts of both track relays *T* and *T'*, and 65 the caution indication circuit of each signal is controlled by a front contact of the corresponding signal relay *R* or *R'*. For example, the clear indication circuit for signal *S'* is from source of current 20 through wire 21, armature contacts 22 and 23, wire 24, signal *S'*, wire 25, to source 20. The caution indication circuit for the same signal is from source of current 20 through wires 21 and 26, contact 27, wire 28, signal *S'*, wire 25, to source 20. Similarly the clear indication circuit for signal *S* is from source 20 through contacts 29 and 30, wire 53, signal *S*, wire 54 to source 20; and the caution indication circuit is from source 20 through wire 55, contact 31, wire 56, signal *S*, wire 54 to source 20. It is of course understood 70 that when both the caution and clear indication circuits of either signal are open the signal will indicate danger.

75 The operation of the system is as follows: Referring to Fig. 1, it will be seen that when no part of the stretch of track A is occupied by a car or train both signals *S* and *S'* will indicate clear for the reason that the clear indication circuits for both signals 80 are closed by the contacts of track relays *T* and *T'*. Referring now to Fig. 2, a car or train *W* has just entered track circuit *a*. This car has opened track relay *T*, whose contacts opened the clear indication circuits 85 of both signals *S* and *S'*. Signal *S'* has therefore changed to danger indication and will continue to give this indication as long as the car *W* remains in any portion of the stretch of track A, because during such time 90 one or the other of the track relays *T* or *T'* will be open. The opening of track relay *T* also closes the circuit for signal relay *R*, which latter relay closes the caution indication circuit of signal *S* as hereinbefore explained. It will be seen that in the front contact of relay *R* closes soon after the opening of track relay *T*, the signal *S* will merely change from clear to caution indication without, in the meantime, indicating danger; if however the closing of relay *R* is considerably retarded, signal *S* will first change to danger indication and will then 105 immediately change to the caution indication. The apparatus and circuits will remain in the condition shown in Fig. 2 as long as the car or train *W* occupies only track circuit *a*. When however the car bridges the rails of track circuit *b* thereby opening track relay *T'*, the closing of back contact 16 of this relay will close another circuit including signal relay *R* as follows: from source of current 10, through contact 16, wire 32, contact 33, wires 34 and 14, relay *R*, wire 15, to source 10. It will be 110 noted that this circuit just traced is the circuit which would normally include relay *R'* but which is now connected with relay *R* due to the fact that relay *R* is already energized. Signal relay *R'* therefore remains deener- 115 120 125 130

gized. After the entire car or train W has left the rails of track circuit *a*, track relay T again closes, thereby opening the circuit which previously included relay R. Relay 5 R continues however, to be energized by the circuit last traced. The condition of the apparatus and circuits is now as shown in Fig. 3. It will be noted that the signal S behind the car still indicates "caution" and 10 that the signal S' at the other end of stretch A still indicates "danger." When the car leaves the rails of track circuit *b*, track relay T' again closes thereby opening the circuit of relay R. The opening of this latter relay 15 opens the caution indication circuit of signal S and closes the clear indication circuits of both signals S and S', and both signals then assume their clear indications. If while the car or train W occupies any portion of the 20 stretch of track A, another car or train should approach the stretch A from siding B, it would find signal S indicating caution and could therefore pass through the stretch under proper control. Similarly any number 25 of following cars may pass through the section from siding B under caution. If however, while the car or train W occupies any portion of stretch A a second car or train should approach the stretch A from 30 siding C, it would find signal S' indicating danger, and would therefore not be permitted to enter the stretch A. If two cars should enter the stretch A at exactly the same instant, they would open both track 35 relays T and T' and both signals S and S' would therefore change to danger indication. The armatures of relays R and R' would, under these circumstances vibrate slightly on their back contacts, but would 40 not be able to close their front contacts 27 or 31, hence neither signal could give a caution indication.

Signals S and S' are preferably located a short distance in advance of the beginning 45 of the track circuits at the respective ends of stretch A, so that the driver of a car or train may observe the change of indication of the signal as he enters stretch A. This will insure that if two cars or trains should 50 enter the stretch A at exactly the same instant as just described, the drivers of both cars or trains would see the signals change to danger indication instead of to caution as is the case when only one car or train 55 enters the stretch A.

The operation of the apparatus and circuits during the movement of a car or train through the stretch A from siding C to siding B would be similar to that herein- 60 before explained for movement in the opposite direction, hence it need not be traced herein.

It will be noted that in case of a broken rail at any point in the stretch A, one of the 65 track relays T or T' will open thereby caus-

ing one signal to indicate caution and the other to indicate danger. It will also be noted that in case of a failure of either of the circuits for the relays R and R', the result will be danger indication by both signals S and S'. 70

Although I have herein shown and described only one form of signaling system embodying my invention, it will be understood that various changes and modifications 75 may be made therein within the scope of the appended claims without departing from the spirit and scope of my invention.

Having thus described my invention, what I claim is:—

1. In combination, a stretch of railway track, signals adjacent the ends thereof for governing traffic in opposite directions through the stretch each signal being adapted to indicate danger, caution and clear, 80 two track relays connected with the rails of the stretch and arranged to be deenergized successively by the passage of a car or train through the stretch the relay which is first deenergized remaining deenergized until after the second relay has been deenergized, means for energizing said track relays, a clear indication circuit for each signal each of which circuits is controlled by both track relays, a caution indication circuit for each signal, two signal relays each for control of one of said caution indication circuits, a normal circuit for each signal relay each circuit including a back contact of one of the track relays and 85 contacts and conductors controlled by each signal relay and operating when the signal relay is energized by the deenergization of the corresponding track relay to disconnect the other signal relay from the track relay 90 back contact with which it is normally connected and to connect the last-mentioned back contact with the signal relay which is 95 energized.

2. In combination, a stretch of railway 100 track, signals adjacent the ends thereof for governing traffic through the stretch in opposite directions, two track relays connected with the rails of the stretch, one of which is deenergized while a car or train occupies 105 one portion of the stretch and the other of which is deenergized while the car or train occupies the remainder of the stretch, the track relay first deenergized remaining deenergized until after the other relay has been 110 deenergized, means for energizing said relays, two signal relays, a normal circuit for each signal relay each circuit including a back contact of one of the track relays, contacts and conductors controlled by each signal relay and operating when the signal relay is energized by the deenergization of 115 the corresponding track relay to disconnect the other signal relay from the track relay 120 back contact with which it is normally connected and to connect the last-mentioned back contact with the signal relay which is 125 energized.

nected and to connect the last-mentioned back contact with the signal relay which is energized, and a control circuit for each signal including a front contact of the signal relay energized by the entrance of a car or train upon the stretch at the end adjacent such signal.

In testimony whereof I affix my signature in presence of two witnesses.

ALBERT L. VENCILL.
